UNITED STATES PATENT OFFICE.

LOUIS C. STAAB, OF LEIGH, NEBRASKA.

WIRELESS RELAY.

Application filed October 10, 1921. Serial No. 506,621.

To all whom it may concern:

Be it known that I, LOUIS C. STAAB, a citizen of the United States, residing at Leigh, in the county of Colfax and State of Nebraska, have invented new and useful Improvements in Wireless Relays, of which the following is a specification.

This invention relates to wireless telegraphy, particularly to receiving mechanism, and has for its object the provision of a novel automatic relay device adapted for interposition in a receiving circuit whereby signals received may be relayed to any desired point.

An important object is the provision of a relay device which includes a moving coil operating between the poles of a permanent magnet and arranged, when deflection occurs, to close a circuit through a signal device, such as a bell, buzzer, or the like, a source of current of course being interposed in the local circuit including the signal.

Another object is the provision of a relay of this character which is provided with means whereby its sensitiveness will be varied so that a greater or less deflection of the moving coil will be required to close the local circuit.

An additional object is the provision of a mechanism of this character which will be simple and inexpensive in manufacture, easy to install and correlate with receiving apparatus, efficient and positive in action, durable in service, and a general improvement in the art.

With the above and other objects and advantages in view, the invention consists in the details of construction to be herein-after more fully described and claimed and illustrated in the accompanying drawings in which:

Figure 1 is a front elevation of my relay device with the cover removed.

Figure 2 is a vertical sectional view therethrough.

Figure 3 is a perspective view of one of the contact arms, and

Figure 4 is a diagram of the complete electrical circuit showing my mechanism interposed in a wireless receiving apparatus.

Referring more particularly to the drawings, I have shown my relay as comprising a suitable enclosing casing 10 which may be formed of any suitable material and which is illustrated as being circular, though it

is to be understood that any other shape might be used, if preferred. This casing is covered by a plate 11 preferably provided with a cut-out portion 12 of the proper shape covered with transparent material 13. Secured within this casing is a permanent magnet 14 of horse-shoe type having pole pieces 15 between which is disposed an armature 16 of suitable material mounted upon a spindle 17 having its ends terminating in sharp points journaled in the concaved ends of bearing screws 18 which are threaded through bars 19 and 20 which are secured upon and insulated from the front and back of the magnet, respectively. This mounting is similar to the mounting of the balance wheel of a watch or clock and the similarity is further enhanced by the provision of a hair spring 21 which has one end secured to the spindle and which has its other end secured to an arm 22 formed on a disk 23 which is rotatably mounted upon the bar 19 by the screw 18 passing therethrough. The disk is held in adjusted position by means of very small screws 24 which pass through arcuate slots 25 in the disk and which are threaded into the bar 19. By this construction it will be seen that the tension of the hair spring may be varied at will so that various different conditions may be met.

The bars 19 and 20 are held in proper spaced relation to the magnet, or the pole pieces thereof, by means of screws 26 and 27 which pass through insulating sleeves 28 and through the bars and into the magnet or pole pieces. Connected with one of the screws 26 and one of the screws 27, are wires 29 and 30, respectively, which are connected with terminals 31 and 32 on the outside of the casing. Also connected with these terminals are flexible conducting cords 33 which carry a telephone plug 34 of ordinary construction.

Carried by the armature 16 and surrounding the same from end to end thereof, is a rectangular elongated loop-like supporting frame 35 which is secured for rotation therewith and which carries one or more convolutions of wire 36 of the size found most advantageous. One end of the wire 36 is connected with a small collar 37 secured upon and insulated from one end of the spindle 17, while the other end of the wire is connected with a small collar 38 secured

upon and insulated from the other end of the spindle and bearing against the bar 20. In this way it will be seen that current passing through the terminals 31 and 32 will also 5 pass through the wire 36, the collars 37 and 38, and through both bars 19 and 20. Extending from the collar 37 is an arm 39, for a purpose to be described. Secured upon some convenient location on the magnet 14 10 is a supporting bracket 40 upon which are secured and insulated from the bracket and from each other, spring contact arms 41 and 42, the former of which carries a platinum contact point 43 and the latter of which carries a silver contact 44. The free end of the contact arm 41 is extended at right angles as shown at 41^a and carries a hard rubber roller 41^b engaging the arm 39 and moved thereby. Pivoted upon the cover 20 plate 11 of the casing is an arm 46 having an angular end engaging the contact arm 42 and provided exteriorly of the cover plate with an operating knob 47.

Connected with the contact arms 41 and 25 42 are wires 48 and 49, one of which is connected with a buzzer, bell, or other signaling device, indicated at 50, and the other of which is connected with one pole of a source of current 51 which has its other pole connected with the signal 50.

In the use of my device, it is of course possible that it be interposed in any one of many varieties of receiving mechanisms or circuits, though in actual practice I 35 prefer to associate it with a receiving station including the usual detector circuit with which is associated two properly connected amplifiers, preferably of the De Forest type. In the diagrammatic view of the complete 40 circuit showing my apparatus in use, I have illustrated the ordinary detector circuit and two of such amplifiers associated therewith and connected with the usual sources of current. These elements or arrangements of 45 wireless receiving apparatus are so well known that it is believed that a detailed description thereof is superfluous in view of the diagram. Suffice to say that the ordinary detector circuit is indicated by the letter A and connected in this circuit by a 50 jack B is the first amplifier C to which is connected, by a second jack D, the second amplifier E which is likewise provided with the jack F.

55 In the actual use of my device the plug 34 is inserted in the jack F, whereupon it will be seen that when a signal is received at the receiving station comprised by the circuit A and the amplifiers C and E, current will pass through the terminals 31 and 60 32, bars 19 and 20, and through the wire 36 which surrounds the armature of my relay device. The passage of current through this wire coil 36 of course induces a current 65 which sets up a magnetic field having a

polarity opposite that of the magnet 14 and the coil consequently moves in the endeavor to bring the two different polarities into harmony. This action results in rotation of the armature and arm 39 whereupon the 70 arm 39 which engages the roller 41^b on the contact arm 41 will move the latter toward the contact arm 42 and this will of course result in engagement of the platinum contact point 43 with the silver contact 44 and this will of course close the local circuit through the source of current 51, wires 48 and 49 and signal 50 so that the latter will be operated. This action will not in any way detract from the local efficiency of the 75 receiving apparatus as only an infinitesimal amount of current is required to pass through the coil 36. After current ceases to flow through the coil 36, it is of course apparent that the contact arm 41 will return 80 to normal position owing to its inherent resilience and the armature and coil will return to neutral position by virtue of the hair spring 21. By rotating the knob 47 the arm 46 may be moved so as to vary the 85 position of the contact arm 42 with respect to the contact arm 41 so as to vary the sensitiveness of the mechanism. In this way it will be seen that the device may be rendered accurate and sensitive under widely 90 varying conditions.

From the foregoing description and a study of the drawings it will be apparent that I have thus provided a simply constructed relay which may be readily interposed in an ordinary receiving station whereby fluctuations in the local circuits under the influence of wireless waves may be caused to close a local circuit associated with a signal device with any ordinary or 100 preferred type located at any point with respect to the wireless receiving apparatus. It is to be noted that I have provided ample means for adjusting the sensitiveness of my 105 relay so that it may be used successfully under varying conditions.

While I have shown and described the preferred embodiment of my invention, it is of course to be understood that I reserve the right to make such changes in the form, construction and arrangement of parts as will not depart from the spirit of the invention or the scope of the subjoined claims.

What is claimed is:—

1. In a relay device, a permanent magnet, an armature journaled between the poles thereof, a coil wound around said armature longitudinally thereof and having its terminals adapted for connection in a circuit, a stationary spring contact, a movable contact for cooperation with said relatively stationary contact, an arm projecting from the armature and engageable with said movable contact for moving the same toward the stationary contact, a rotatably adjustable 120
- 125
- 130

arm member engaging said relatively stationary contact for regulating the position thereof.

2. In a relay device, a permanent magnet, 5 an armature journaled between the poles thereof, a coil wound around said armature longitudinally thereof and having its terminals adapted for connection in a circuit, a stationary spring contact, a movable contact for cooperation with said relatively 10 stationary contact, an arm projecting from the armature and engageable with said mov-

able contact for moving the same toward the stationary contact, a rotatably adjustable arm member engaging said relatively stationary contact for regulating the position thereof, said first named arm being carried by a disk rotatably adjustably mounted upon the armature whereby to regulate the initial position of the movable contact with 15 respect to the stationary contact.

In testimony whereof I affix my signature.

LOUIS C. STAAB.
